UNITED STATES PATENT OFFICE

LOUIS POMRENKE, OF TRENTON, MICHIGAN

WINDOW VENTILATOR

Application filed January 30, 1929. Serial No. 336,290.

This invention relates to an improved ventilator apparatus, particularly adapted for installation in the side window of a bus or other motor vehicle, railroad car, and the like, and has for its object an improved organization of parts whereby an outflow of air of regulatable degree may be induced from the interior of the vehicle without any unpleasant effect upon persons seated there-
within, and yet which will adequately effect a change of air therewithin without the necessity of having the window open to an uncomfortable degree, as would be the case particularly if a cross wind were encountered.
15 If for any reason it is desired to temporarily dispense with the apparatus, it is easily removable and replaceable, or, if preferred, it may be left in and closed practically air-tight by the manually effected sliding of the cover plate or closure member.

In the drawings:

Figure 1 is a side elevational view of a part of a vehicle body showing my improved device in position therein.
25 Figure 2 is an enlarged side elevational view taken from the same position as Figure 1.

Figure 3 is a sectional plan view taken along the line 3-3 of Figure 2, and looking in the direction of the arrows there shown.

Figure 4 is a perspective of the device looking toward the interior face or side.

Figure 5 is a cross sectional view taken along the line 5-5 of Figure 3 and looking in the direction of the arrows there shown.

A indicates a vehicle body of any desired construction, and B the partially lowered window, the space between the top edge of which and the top of the window frame being designed to be occupied by my improved ventilator. This consists essentially of a rectangular frame C, preferably of channeled cross-sectional form, as brought out in Figure 4. Slidably supported within this channel is a closure member F provided with a knob G for convenient actuation, this closure piece being of approximately half the length of the ventilator as a whole. When in drawn back position, so that the ventilator is functioning to its full capacity, this

closure panel F lies in spaced parallel relation with the fixed panel E, which extends about half of the length of the ventilator as a whole. The forward end of this fixed panel E, which is located on the outside of the shell, 55 that is, on the outside of the car, is preferably curved slightly at the point H so as to form the rear boundary of the space occupied by a series of inclined vanes or baffle members which extend angularly outward from the forward end of the ventilator, being supported at their top and bottom edges by the tapering border pieces J. The forward curved edges of the border pieces are spanned by the angular piece K the preferred form of which, 60 as brought out particularly in Figures 3 and 4, extends for a portion of its length practically right angularly to the plane of the ventilator as a whole, and then turns quite sharply rearwardly. Thus, as regards the 65 space between the rearward edge of the member K and the slightly outbent portion H, the space between the bordering members J is left open, except for the spaced positioning between them of the vanes or baffle members, 70 which it will be noted, from an inspection of Figure 3 particularly, are preferably placed at slightly progressive angles relatively to the plane of the ventilator, beginning with a quite sharp angle as regards the positioning 75 of the vane M near the curved portion H and approaching much more nearly a perpendicular position as regards the slant of the vane N next adjacent the wind breaker portion K, these vanes or baffles being of progressively 80 lesser breadth accordingly. When, however, it is desired to close the slide panel F by moving it to the forward portion of the ventilator shell, this open condition as regards the more or less indirect communication with 85 the outer air is negatived by the presence of the slide across the bottom or inner edges of the several vanes or baffles. To prevent rattling, I preferably provide a leaf spring L on the outer side of the closure panel F, 90 which is curved sufficiently to frictionally engage the inner edge of the several baffles as the closure panel is drawn thereacross.

The operation of my improved device is as follows: Since the body of the end plate K 100

is positioned substantially perpendicularly to the plane of the ventilator as a whole, which latter in turn parallels the course of the vehicle, this end plate receives the direct transverse impact of the wind, illustrated by the arrow W, as the vehicle travels along, though its outward extent of only about three or at the most four inches is negligible as regards wind resistance to the travel of the vehicle as a whole. The wind thus striking the perpendicular portion of this impact plate swirls around and over the curved outer edge thereof toward the rear or fixed panel E, leaving more or less of a vacuum immediately adjacent the outer edges of the several vanes or baffle plates, on something the same principle that the wing of an aeroplane is made more or less thick at its forward edge in order to benefit from the lifting influence of the partial vacuum created immediately above it by the corresponding initial and then deflected impact of the wind against its forward edge. The induced swirling of the air about and over the curved outer edge of this impact plate results in the air inside the vehicle being drawn outwardly between the several vanes by the vacuum condition thus created immediately adjacent their outer edges, as emphasized graphically by the several curved line arrows, X, Y and Z, shown in Figure 3, and it has been my experience from repeated severe tests of such a device that proportionately to the exposed air passage space as regulated by the position of the closure panel F a remarkable degree of outward draught is secured, and that this is materially aided and guided by the slightly progressive angular inclination of the several baffles as they lie spacedly adjacent one another from front to rear. It will of course be obvious that the size of the exposed space between the vanes or baffles can be easily regulated as regards the actual outflow of air from the vehicle by the selective positioning of the slidable closure panel F.

It will thus be seen that, without resorting to the use of an external wall piece, which with the main body of the ventilator would serve as more or less of a funnel, I have produced an efficiently functioning ventilator mechanism, whereby an adequate quantity of bad air may be withdrawn from the vehicle with a minimum of discomfort to the occupants, compensation for which in the form of indrawn fresh air can be confidently looked for through the various incompletely closed cracks and apertures of the vehicle enclosure. Modifications as to the number and angularity of the vanes, as well as the details of the frame and door or closure panel as such, can be indulged in without departure from the fair spirit of my invention, even to the degree of entirely omitting the slidable closure panel F if desired.

What I claim is:

1. A window ventilator, having in combination with a partially apertured frame, a slidable closure member adapted to move, in spaced parallel relation to the closed portion of said frame, a wind impact member extending perpendicularly outward from the forward end of said frame and adapted to curvingly deflect the air impinging against it toward the rear portion of said frame and relatively over the forward portion thereof, and a plurality of baffle members spacedly positioned across the normally open portion of the frame and adapted to cooperate with one another and with the flanking edge portions of the frame in guiding outside the vehicle the exhausted air which is outwardly drawn by the induced vacuum conditions prevailing just outside of the outer edges of said baffle members.

2. In a window ventilator, in combination with a frame having a plurality of variantly angular baffle members spacedly positioned opposite its open portion, a wind impact and deflecting member extending substantially perpendicularly to the plane of the frame as a whole and at one end of said series of baffle members, adapted to curvingly deflect the air over and to the rear of the outer edges of said baffle members and to resultantly create a tendency toward vacuum conditions immediately adjacent thereto, and means for regulatably closing the space within the frame opposite said baffle members.

3. In a window ventilator, in combination with a frame adapted for removable positioning in the plane of the window of a vehicle, the rear portion of said frame being provided with a permanent closure plate, a slidable closure element positioned within said frame in spaced parallel relation to the plane of said permanent closure plate and adapted to be moved to position of closure as to that portion of the frame not occupied by said permanent closure plate, a wind impact panel extending perpendicularly outward from the forward portion of the normally open part of said frame, adapted to deflect the air over and rearwardly of the space immediately outside of the normally open part of the frame, thereby creating a tendency toward a vacuum condition at that point, and a plurality of angularly positioned and progressively narrowing baffle plates spacedly positioned across the normally open part of said frame, between which air is adapted to be drawn outwardly by the aid of the partial vacuum condition created adjacent their exposed outer edges.

4. A window ventilator, comprising a frame provided with a fixed panel and a slidable panel whereby when the latter is moved to the forward end of the frame its complete closure may be effected, a plurality of angularly spaced vane members of pro-

gressively decreasing breadth from the front to the rear of the open portion of said frame, and a wind impact plate extending perpendicularly to the plane of said frame in front 5 of the most forwardly located and broadest one of said vanes, whereby the air primarily striking thereagainst is curvingly deflected toward the space adjacent the outer rearward face of said frame, thereby creating 10 a tendency toward a vacuum condition immediately adjacent the outer edges of said vanes and resultantly effecting an outward movement of air through the spaces between said vanes, subject to the regulated positioning of 15 said slideable panel relatively thereto.

5. In a window ventilator, in combination with a frame provided with a fixed panel and a sliding panel, the latter when in forward position being adapted to close that portion 20 of the frame not occupied by said fixed panel, a series of baffle members spacedly supported in variably angular position across the normally open portion of said frame, said baffle members being of graded breadth from front 25 to rear of said open portion of said frame, and a wind impact element extending substantially perpendicularly outwardly from the forward end of said frame, whereby the air primarily striking thereagainst is cur- 30 ingly deflected toward the rear outer face of said frame, thereby creating a partial vacuum in the space adjacent the outer edges of said baffle members, for inducing an out- 35 flow of air through the spaces between them and through the open portion of the frame 40 from the interior of the vehicle wherein the ventilator is positioned.

6. In a window ventilator, the combination, with a frame, of a pair of closure panels 45 positioned therewithin, one of said panels being slideable for regulatably effecting the closure of the space within the frame not occupied by the fixed panel, a wind impact plate extending outward from the forward edge of 50 that portion of the frame remote from that occupied by the fixed panel, and a plurality of baffle members of progressively decreasing breadth spacedly positioned across the normally open portion of said frame, between 55 which air is adapted to be drawn outwardly from the interior of the vehicle in response to the created vacuum tendency just outside the outer edges of said baffle members, due to the curved path of the deflected air from 60 said wind impact plate toward the rearwardly located fixed panel portion of the frame.

7. A window ventilator, comprising in combination, a frame member adapted to be positioned in the space made available by 65 the lowering of the window of a vehicle, selected portions of the top and bottom portions of said frame being of tapering width as viewed from above or beneath, a plurality of spacedly disposed vane members of pro- 70 gressively diverse width supported at their

ends by said tapering frame portions in positions of oblique angularity relatively to the plane of the frame as a whole, thereby constituting between them a plurality of air egress channels from the interior of the vehicle, and a wind breaker member supported at the forward end of said frame, in substantially perpendicular relation to the plane of the frame as a whole, adapted to curvingly deflect the air impinging against it over the 75 exposed outer edges of said vane members, thereby creating a tendency toward a vacuum condition adjacent the outer ends of the air egress passages formed thereby.

In testimony whereof I sign this specifica- 80

LOUIS POMRENKE.
